 Del., a corporation of Delaware

Application September 5, 1940, Serial No. 355,488

19 Claims.

(Cl. 300—11)

This invention relates in general to a machine for bristling brush blanks, and more particularly to a continuous indexing cam mechanism for speeding up the operation of the machine.

In the prior art, as exemplified by Patent No. 1,846,141, a blank holder, containing a plurality of blanks, is reciprocated laterally and longitudinally by means of cams between each single tuft setting operation in one blank, and this blank is thus moved about below a stationary position for the vertically reciprocable but otherwise stationary tuft setting needle, until all the tufts or knots of bristles are set. Then the setting mechanism is stopped, a screw feed connected with the holder operates during cam dwells, and the holder is thus traveled laterally approximately the width of a single blank clamping means, so that the next blank in the holder may be moved into position to be operated upon. Such a machine loses the time during this feeding of the blanks, when the setting mechanism is idle, and the jarring and vibration resulting from the stopping and starting of the setting mechanism has a deleterious effect on the entire machine and the product.

The principal objects of the present invention include the provision of a brush bristling machine which avoids these defects of the prior art; the provision of a mechanism which obviates the necessity of stopping the setting mechanism between blanks, so that the vibration and loss of time incident to the prior art machines is avoided; the provision of means to feed the blank holder laterally one step between each tuft setting operation, so that when a blank has been bristled, it is only necessary to advance the holder a fraction of the distance formerly required to put the next blank in setting position; and the provision of a brush bristling machine which is faster and smoother in operation than any of the prior art devices. We have referred to the setting operation as a matter of convenience only, as the same mechanisms also provide improved results from the drilling operation in the same manner.

Other objects and advantages of the invention will appear hereinafter.

Reference is to be had to the accompanying drawings, in which

Fig. 1 is a partial plan view of the continuous indexing mechanism as applied to a tooth brush bristle setting machine;

Fig. 2 is an end elevation, looking in the direction of arrow 2 in Fig. 1;

Fig. 3 is a front elevation, looking in the direction of arrow 3 in Fig. 1;

Fig. 4 is a front elevation of the eccentric adjusting means;

Fig. 5 is a broken away plan view, looking in the direction of arrow 5 in Fig. 4;

Fig. 6 is a detail view of a brake band;

Fig. 7 is a broken view of a cam wheel; and

Fig. 8 is an enlarged plan of a brush blank, showing the order of the setting operations.

Referring to the drawings in detail, 10 indicates a slide which is movable longitudinally of the machine in suitable guides, not shown, by means of a cam 12. This cam has a cam track 14 which comprises twenty-five angularly equal stations, in which track runs a roller 15 on a lever 16 pivoted at 18 on a stationary part of the machine. This lever has a second roller 20 at its other end, and this roller runs in a track in a plate 22 adjustably carried as by slot and bolt connection 24 on a projection 26 which is integral with the longitudinal slide 10.

Slide 10 is adapted to be moved transversely of itself by means not here shown, but which may comprise a carriage similar to that at 71 in Patent No. 1,846,141. It is not thought necessary to illustrate this carriage and its actuating cam means, as these are clearly shown in the same relation in said patent.

The brush blanks 28 are carried in a series of holders 30, each of which is provided with a plurality of seats 32 on its upper surface shaped to fit the particular brush, and the bristle holding parts of the brushes may be secured in place on the holder by plate 34 or other means. Each holder is provided with gibbs 36 arranged longitudinally of the slide. On its undersurface each holder may be provided with a half-nut, similar to that at 78 in Fig. 33 of the aforementioned

patent, to threadedly engage with a screw 40 which is journaled on the slide as at 42. A bracket 43 aids in holding the parts in assembled relation. It is to be noted that slide 10 carries screw 40 with it in all its movements, and as holders 30 are in mesh with the screw, the holder will also be carried in conformance with slide 10; but in addition the holder is subject to a longitudinal feed with relation to slide 10, due to any turning of the screw 40. The screw shaft is provided with a gear 44 fixed thereon, and a brake band 46 having a shoe 48 and an adjusting screw 50. The gear 44 and brake 46 are mounted on an enlarged end of the screw shaft, as shown in Fig. 1. The brake is for the purpose of holding screw 40 against any possible undesired turning

50
 55

movement, so as to promote accuracy in the feed.

At the left hand end of slide 10, an integral support 52 extends outwardly, and this support carries a bearing housing 54 for the reception of a shaft 56. This shaft carries a sprocket 58 which is continually rotated by chain 60 or other means during the operation of the machine. A circular connector plate 62 is bolted or otherwise secured to one side of the sprocket, and this plate is machined to form a slot 64 for the sliding reception of a lateral support 66 on an eccentric 68, see Figs. 4 and 5. The support 66 is provided with a threaded aperture thru which extends a correspondingly threaded bolt 70 which is held against longitudinal movement by a plate 69 and a shoulder 71 on the plate 62. Upon turning the bolt, the support 66 and thus eccentric 68 will be moved radially of the shaft, and the eccentricity of the former is thereby made variable. The assembled eccentric, plate, and sprocket may be held to the shaft by means of a nut 72.

The eccentric 68 is provided with a flange 74 to form a peripheral channel for the holding reception of a strap 76 which is split at 78 and tapped at the split for adjustable reception of a bolt 80. After adjustment, the bolt may be clamped by a screw 82. As best shown in Fig. 2, bolt 80 is pivoted to one arm 84 of a bell-crank, the latter being pivoted on a short stud 86, and the other arm 88 of the bell-crank has a pawl 90 urged by spring 92 towards engagement with teeth 94 on a ratchet 96. The ratchet is fast to a gear 98 on the stud 86, and this gear is in constant mesh with gear 44 on screw shaft 40.

In the operation of the device, the sprocket 35 58 is continuously rotated in exact timed relation to the bristle setting mechanism, and by means of the pawl and ratchet, the screw shaft 40 is intermittently rotated. The intermittent rotation of the screw occurs between each tuft 45 setting operation, when the needle is elevated, so that between each knot or tuft placement, the holder 30 is moved to the right in Fig. 1, one step, with relation to slide 10. The cam 12, having a plurality of stations, is designated to move slide 10 and holder 30 with it, to compensate for the screw feeding of the holder on the slide, at each cam station, so that the knots or tufts will be correctly located in their drilled holes. The movements due to cam 12 and the 50 screw shaft affect the holder 30 only as to longitudinal movement thereof, i. e., lateral movement of the brush blanks. The longitudinal movement of the blanks is obtained by a cam 55 not here shown but similar to cam 65 in Patent No. 1,846,141, which forms no part of the present invention.

As the holder 30 is moved to the right in Fig. 1 by the screw, and cam 12 compensates for this movement depending on the locations of the knots or tufts, it will be seen that the last knot, #25 in Fig. 8, will be set between cam stations 100 and 102 in Fig. 1, and this knot is at the side of the blank adjacent the side of the next knot to be inserted, i. e., #1 in the next blank. Thus, only a small forward movement of slide 10 is necessary to complete the cycle thereof and to aline the setting needle with the first hole in the succeeding blank, instead of a movement of the distance between corresponding knots, as in the prior art. This small forward movement is accomplished by the single cam station 102 in Fig. 1, which will be seen to be at a relatively sharp angle so as to pivot lever 16 thru a greater angle than that used between the knots in a 75

blank. Hence, the new blank will now take the starting position of the just bristled blank, and the bristling operation is repeated on the next revolution of the cam.

In other words, point 104 on cam 12 represents initial placement of the parts, and when the roller 15 is at this location, #1 knot or tuft is set. Upon retraction of the setting needle, cam track 14 will actuate lever 16 to move slide 10 and with it holder 30 in a direction to compensate for the forward feed of holder 30 due to screw 40, so as to bring drilled hole #2 into correct position relative to the setting needle. This action continues as the cam rotates, with screw 40 feeding holder 30 between each setting operation, until, at station 102, the holder 30 has been moved relative to slide 10, nearly the distance between brushes, but a further movement is necessary to complete the cycle and bring slide 10 to original position. This is accomplished by station 102, and the simultaneous screw feed at this station completes the movement of holder 30 so that the next blank now assumes the position formerly held by the just finished blank.

By means of screw feeding the holder 30 an equal amount between each knot, instead of only between blanks, the number of cam stations is reduced from twenty-nine to twenty-five, since heretofore it was thought necessary to provide an interval of four idle stations to allow for movement of the holder the distance of a complete blank. Therefore, by use of the present device, it is possible to set a knot (or drill a hole) between each station on the cam 12, the drills and needles do not have to be stopped between blanks, and the entire cam is now useful, instead of having four idle stations, as in the prior art.

In the drawings and description above, the invention has been illustrated in a machine for making a twenty-five knot brush, but it will be clear that by changes in the cams and ratchet, brushes of any desired number of knots may be made. It is only necessary to provide a ratchet having as many teeth as the brush has knots, in order to feed the holder by the screw between each setting and drilling operation, and to provide the cams with the required number of stations.

In any case, it is to be observed that since each station on cam 12 is an active or useful station, the drilling and setting operations are continuous, from brush to brush and from holder to holder, without any interruption or stop action. Thus the action of the machine is just as if a single continuous piece were being operated upon as long as the machine runs, the time interval between each drilling or setting operation being equal at all times.

In cases where the spacing of the brushes in the holders is to be changed, it is only necessary to change the ratio of gears 44 and 98 to compensate for the variation in the feed in the travel of the holder.

Having thus described our invention and the advantages thereof, we do not wish to be limited to the details herein disclosed, otherwise than as set forth in the claims, but what we claim is

1. In a bristling machine, the combination of a slide, means to reciprocate said slide in directions transverse to each other, a holder movably mounted on said slide and adapted to receive a plurality of blanks to be bristled; with means to move said holder in relatively parallel relation to a movement of said slide in one direction

during each movement of said slide due to said reciprocating means.

2. In a bristling machine, the combination of a slide, means to reciprocate said slide in a predetermined cycle in at least two angular directions, and a blank holder on said slide and movably mounted thereon; with means to feed said holder in a single direction relative to said slide during the reciprocation of the latter in two directions.

3. In a bristling machine, a slide, means to reciprocate said slide in transverse directions in a predetermined cycle, a movable blank holder, spaced receiving means on said holder for a plurality of blanks, and means to move said blank holder in parallel relation to a movement of said slide and simultaneously with the reciprocatory motion of the latter.

4. In a bristling machine, the combination of a movable slide, means to reciprocate said slide in at least two transverse directions in a predetermined cycle, a blank holder on said slide, said holder being mounted for sliding movement; with means mounted on said slide and engaging said holder to regularly and intermittently advance said holder with relation to said slide and in one only of said directions during each movement of the latter.

5. In a bristling machine, the combination of a slide, means to reciprocate said slide in mutually transverse directions a predetermined cycle, a blank holder mounted on said slide for movement therealong in one direction, spaced means on said holder for receiving a plurality of blanks; with means on said slide to intermittently move said holder in relatively parallel relation to said slide during the latter's movement, said means being effective to move said holder a distance between blank centers during a substantially complete cycle of said slide.

6. In a bristling machine, the combination of a slide, a holder adapted to receive a plurality of blanks to be bristled, said holder being mounted on said slide for movement with relation thereto, a cam for moving said slide, and a screw shaft mounted on said slide for movement therewith and threadedly engaging said holder; with means to intermittently rotate said screw to move said holder relative to said slide during and parallel to the movement of said slide by said cam.

7. In a bristling machine, the combination of a slide, a blank holder movably mounted on said slide, and means to reciprocate said slide in a predetermined cycle; with a screw shaft on said slide and engaging said holder, and means on said slide and movable therewith to intermittently rotate said screw, said means being effective to rotate said screw and thereby advance said holder during the reciprocatory movement of said slide.

8. In a bristling machine, the combination of a slide, a blank holder on said slide, means on the latter movably mounting said holder, a cam having a connection with said slide, said cam being effective to reciprocate said slide in generally irregular steps in cycles; with means to intermittently and regularly move said holder in one direction on said slide in steps, the movements of said slide and said holder being substantially simultaneous.

9. In a bristling machine, the combination of a slide, said slide being adapted to movably mount a blank holder, and means to substantially continuously reciprocate said slide; with means

to feed said holder along and generally parallel to the movement of said slide, said means comprising a screw shaft, a ratchet operatively connected thereto, a member adapted to be continually rotated and mounting a pawl, and said pawl and ratchet being in operative relation, whereby said holder may be fed along said slide in steps.

10. In a brush bristling machine, a support, a slide on said support, driving means on said slide, brush blank holders adapted to engage said means, means for moving said slide, and means effective to intermittently operate said driving means so that said holders are each moved in equal increments along said slide in one direction between each single bristling operation and between all such operations.

11. In a brush bristling machine, a support, a slide on said support, a screw mounted to rotate on said slide, a ratchet to operate said screw intermittently, brush blank holders adapted to engage said screw, continuous means to operate said ratchet so that said holders intermittently advance with relation to said slide, a cam adapted to intermittently move said slide, said ratchet and cam being effective to move said holders and slide, respectively, at the same time between each single bristling operation, whether between such operations in a single blank, between blanks, or between holders.

12. In a brush bristling machine, the combination of a slide and means to reciprocate said slide thru a cycle including movements in direction mutually transverse; with a brush holder on said slide, said holder being movable relative said slide in one direction only, and means effective to move said holder step by step along the slide in said last named direction, said means being selectively interchangeable to provide a variant degree of travel in the steps.

13. In a device of the class described, the combination of a slide, and means to move said slide thru a cycle; with a driving means on said slide, gear means to intermittently operate said driving means, a holder engaged with driving means so as to be movable step by step on and parallel to a motion of said slide, a plurality of spaced brushes on said holder, and said gear means being constructed and arranged to be selectively interchangeable with gears of different ratio whereby said brushes may be spaced to a different degree.

14. In a device of the class described, the combination of a slide and means to move said slide repeatedly in a cycle, said means comprising a cam track having a series of stations; with a driving means on said slide, a holder engaged by said driving means, means to intermittently operate said driving means to travel said holder step by step along and generally parallel to a motion of said slide, said operating means having actuating elements corresponding in number to the stations in the cam track, and said driving means and cam being selectively interchangeable with a driving means and cam having different but still corresponding numbers of actuating elements and stations respectively.

15. In a device of the class described, the combination of a slide and means to move said slide repeatedly in a cycle; with a holder on said slide, means effective to travel said holder along and generally parallel to a motion of said slide, means to operate said traveling means intermittently so that said holder may be traveled step by step, said operating means being of interchangeable nature, whereby a variation in the lengths of the steps may be produced.

16. In a machine of the class described, an element adapted to be moved in at least two transverse directions, a brush blank holder slidably mounted on said element, and means to move said holder along said slide in one of said directions, said means being operative to move said holder during each movement of said slide in either direction.

17. In a machine of the class described, an element adapted to be moved in transverse directions, a brush blank holder mounted on said element for movement therealong in one direction, and means to move said holder in said one direction during each movement of said element in either direction.

18. In a brush boring and setting machine, the combination of a slide, means to reciprocate said slide in at least two transverse directions, and

a blank holder movably mounted thereon; with means to move said holder step by step in a direction parallel to one direction of movement of said slide between each boring or setting operation.

19. In a machine of the class described, a slide adapted for reciprocation in at least two transverse directions, a brush holder mounted on said slide for movement therealong in one direction of said reciprocation, means to move said holder simultaneously with the movements of said slide, the movements of the slide thereby modifying the distances traveled by said holder with relation to a fixed point.
